Fig. 1

Fig. 2

FIG. 1 is a perspective view of a crib showing the design of my invention.

FIG. 2 is a sectional view along line II—II of FIG. 1. The back of the panel is plain and unornamented.

The dominant features of my design reside in those portions shown in full lines on the drawing and consists of the continuous three-dimensional scalloped design framing the headboard as shown.

I claim:

The ornamental design for a crib, substantially as shown and described.
